COMBINED ASH TRAY AND PIPE KNOCKER

Dudley Courtenay, Summit, N. J.

Application December 19, 1952, Serial No. 22,788

Term of patent 7 years

(Cl. D85—5)

To all whom it may concern:

Be it known that I, Dudley Courtenay, a citizen of the United States, residing at Summit, in Union County, State of New Jersey, have invented a new, original, and ornamental Design for a Combined Ash Tray and Pipe Knocker, of which the following is a specification, reference being had to the accompanying drawing, forming a part hereof.

Figure 1 is a top plan view of a combined ash tray and pipe knocker, showing my new design with the tilting cover in closed position;

Figure 2 is a side elevational view thereof, partly broken away, showing the pipe knocker portion below the tilting cover; and

Figure 3 is a bottom plan view thereof, to a reduced scale.

I claim:

The ornamental design for a combined ash tray and pipe knocker, substantially as shown and described.

DUDLEY COURTENAY.
